PUTTING GAME CLUB HEAD

August T. Johnson, Winters, Calif.

Application April 19, 1948, Serial No. 145,819

Term of patent 14 years

(Cl. D34—5)

To all whom it may concern:

Be it known that I, August T. Johnson, a citizen of the United States, residing in Winters, county of Yolo, State of California, have invented a new, original, and ornamental Design for Putting Game Club Head, of which the following is a specification, reference being had to the accompanying drawing, forming part thereof, in which:

Figures 2 and 3 are elevational views taken from opposing sides, respectively, of my putting game club head.

I claim:

The ornamental design for a putting game club head, substantially as shown.

AUGUST T. JOHNSON.
